(57) **CLAIM**

The ornamental design for a combined removable drawer and diaper bag, as shown and described.

DESCRIPTION

FIG. 1 is a front elevation view of the diaper bag;
 FIG. 2 is a perspective view, showing the drawer partially removed from the diaper bag;
 FIG. 3 is a perspective view of the drawer;
 FIG. 4 is a front elevation view thereof;
 FIG. 5 is a rear elevation view thereof;
 FIG. 6 is a left side elevation view thereof, the right side being a mirror image;
 FIG. 7 is a bottom plan view thereof; and,
 FIG. 8 is a top plan view thereof.

The portions of the drawings shown in broken lines illustrate environment and form no part of the design sought to be patented.
